UNITED STATES PATENT OFFICE.

DANIEL J. WEIR, OF NEW YORK, N. Y.

DESIGN FOR A PULLEY-FRAME.

SPECIFICATION forming part of Design No. 16,113, dated May 26, 1885.

Application filed April 16, 1885. Term of patent 14 years.

To all whom it may concern:

Be it known that I, DANIEL J. WEIR, of the city, county, and State of New York, have invented and produced a new and original Design for Pulley-Frames, of which the following is a full, clear, and exact description.

Reference is to be had to the accompanying drawings, forming part of this specification, in which similar letters of reference indicate corresponding parts in both the figures.

Figure 1 is a side elevation of my newly-designed pulley-frame, and Fig. 2 is a front or edge view thereof.

The leading feature of my design consists of heart-shaped side or cheek pieces of the frame. A is the top of the pulley-frame, and B B

the side or cheek pieces thereof, which show reverse curves *a a* at their side edges, and ovals *b b* at their lower edges, which join at *d*, thus imparting a heart-shaped configuration to the frame.

I claim—

The herein shown and described design for a pulley-frame, consisting of the representation of a frame with reverse-curved sides *a*, terminating at their lower ends into ovals *b*, and at their upper ends into an extension or top, A.

DANIEL J. WEIR.
